UNITED STATES PATENT OFFICE.

CHARLES G. HENSLEY, OF BROOKLYN, NEW YORK.

DEVICE FOR IMPRESSING SOUND-WAVES ON DIAPHRAGMS.

1,397,048.

Specification of Letters Patent.

Patented Nov. 15, 1921.

Application filed January 31, 1918, Serial No. 214,629. Renewed April 6, 1921. Serial No. 459,016.

To all whom it may concern:

Be it known that I, CHARLES G. HENSLEY, a citizen of the United States, and a resident of the borough of Brooklyn, city and State of New York, have invented certain new and useful Improvements in Devices for Impressing Sound-Waves on Diaphragms, of which the following is a specification.

10 The present invention relates to a device for impressing sound waves on a diaphragm. The device is adapted for use as a recorder for making phonograph records, as a microphone or telephone transmitter, or for any 15 other purpose where sound waves are impressed on a diaphragm. In the drawing I have shown a device provided with a diaphragm and a stylus lever for recording sound waves on a record for use in phonographs but it is to be understood that the 20 operation of my invention is practically the same regardless of whether the diaphragm operates a stylus lever or creates impulses in an electric circuit.

25 My object is to remove all the defects present in previous devices for collecting and impressing sound waves on a diaphragm.

In all previous attempts to collect and 30 impress sound waves on a diaphragm, so far as I am aware, some instrument such as a horn or concentrator having an open air space has been used to collect and concentrate the sound waves. Usually the collecting and concentrating device has been in 35 the nature of a horn or some such equivalent means with an open air space and with a larger area at the open end where the sound waves enter and with a smaller area 40 where the sound waves strike the diaphragm. Such devices operate on principles almost contrary to the laws of acoustics and are therefore very inefficient. In recording sounds on phonograph records, for instance, 45 it is necessary to place the speaker or artist very close to the receiving end of the horn in order to make what is now considered a loud record. This results in recording the sounds so that they reproduce in an unnatural way and in the case of a singer for 50 instance, the reproduction has the same effect as if one listened to the singer at a short distance from the artist's mouth and

as one seldom hears a singer under such circumstances, the effect does not seem natural. 55

If the artists are placed farther away from the horn, even a few feet, the reproduction is then unsatisfactory because the sounds make it appear as if the artists were very distant from the recording instrument 60 and much of the finer detail is lost.

Another difficulty with the present recorders is, that it is very difficult to get good recordings of a number of voices or instruments at one time because it is impossible 65 to group all the singers or all the players near the recording instrument and the result is a far away effect when the records are played.

Furthermore, while attempts have been 70 made for years to secure louder recordings the record manufacturers have reached their limit in this direction without obtaining the results they desired. It would seem to many that to make louder records it should only 75 be necessary to use larger recording horns and have larger portions of the total sound waves come within the recording horn, but such is not the case. Beyond certain very narrow limits it is impossible to increase 80 the amplitude of recording to produce loud records, by increasing the size of the horn. Beyond certain limits the recordings are less pronounced as the size of the horn is increased and the sounds are not recorded 85 true but are distorted, and the latter fact has led many to refer to the distorted sounds as "extraneous sounds."

Another serious disadvantage in the present systems of sound recording is, that in 90 order to obtain sufficiently loud recordings it is necessary to use horns made of materials which lose much of the quality of the natural sounds. For instance, many of the record manufacturers use zinc or other metallic horns and these either impart a false or metallic quality to the recorded sounds or they fail to record the full true quality. Zinc is but slightly resonant, i. e., it is susceptible to very slight bending or vibration 100 under the action of sound waves so that it really bends to the principal or main tones and to only some and not all of the overtones and for this reason many of the overtones are not recorded and much of the beauty of 105 the music is lost. On the other hand, this

very same characteristic causes the main or principal tones to be recorded louder than would be the case if a more resonant material were used for the horn. Many wooden horns of various shapes have been used for making sound records but owing to the resonant nature of wood it presented other difficulties in the recording systems heretofore used. In telephone practice many, if not all, of the above difficulties are met with. It is difficult to provide a loud transmitter without multiplying all the defects of sound concentration to such an extent as to outweigh the advantages of such an instrument.

One important reason why it has heretofore been impossible to accomplish the desired results is because the attempts have been contrary to one of the main laws of acoustics. It is well known that a megaphone or horn, when sound waves are introduced into the smaller end, has the effect of amplifying the sound waves and of directing them in some general direction. This principle is properly employed in the reproduction of sounds. In the recording or transmission of sounds, however, it has been improperly used. When, in the recording or transmission of sounds the waves reach the larger end of the horn or collector, the large body of air, as well as the material of the horn, tend to reflect the sound waves away from the horn, and away from the smaller end through which they must pass in order to be recorded or transmitted.

This is due to well known laws of acoustics, to the principle of resonance or amplification.

Another disadvantage of the present recording systems is that it is impossible to secure anything approaching uniform results. Good records are obtained by having the artists make a number of records and by selecting those which are best. The reasons why the same artist will record well at one time and not at another are not understood even by the most expert recorders and the difficulties are charged to weather conditions and such uncontrollable elements which, as a matter of fact, have very little to do with the results obtained. The defective results are due more to acoustical errors not heretofore understood.

The object of my invention is to overcome each and all of the defects of recording and transmitting instruments and to make possible the attainment of results which were heretofore impossible.

Instead of having a horn with a large body of air therein I provide a collector or concentrator having a comparatively small body of air and in this way I reduce the resonance of the device so that it is practically negligible. In reducing the body of air, however, I do not reduce the sensitivity or efficiency of the device but increase

it, because I am able to secure the effective energy of a large portion of the sound wave and to apply the energy to the recording or transmitting diaphragm.

Furthermore, as I increase the size of the device I do not increase the size of the body of air therein in the same degree as in the horns heretofore used. In fact, one dimension of the air space may be kept at a minimum and for this reason there is almost no limit to the size the device may attain. The effectiveness of the device, *i. e.*, the recording or transmitting power, will increase as the size of the device is increased without being offset or counteracted by elements heretofore encountered.

The sounds impressed on the diaphragm are not distorted or rendered unnatural, no matter what the size of the device may be, because of the comparatively small air space and slight resonance within the device. There will be no confusion of sounds even where sounds from several voices or instruments are being simultaneously recorded or transmitted. The source of the sound may be very close to the device and there will nevertheless be no blasting of the diaphragm. Louder recordings may be had than with any previous device. The recordings will be full and loud even though the source of the sound be much farther away from the instrument than in prior practice. The artist instead of singing, talking, or playing close to the instrument may be a room length away and all audible sounds will nevertheless be recorded.

The device may be made of materials which will neither add false quality to the sounds nor subtract the natural quality. Sounds from any voice or instrument may be recorded with every natural overtone. In the preferred construction the device is made of wood preferably a soft, mellow wood such as pine or spruce. Although I am not the first to make a recorder or transmitter of wood I believe I am the first to obtain the desired results with this material.

Other advantages will be made apparent by the detailed description of one embodiment of my invention.

In the drawing forming part of this application,

Figure 1 is an end elevation of the device looking at the end having the recording or transmitting diaphragm,

Fig. 2 is a sectional view, taken on the line 2-2 of Fig. 1, and

Fig. 3 is a sectional view, taken on the line 3-3 of Fig. 2.

In the drawing 1 indicates the diaphragm on which the sound waves are to be impressed. In the illustration this is shown as a diaphragm to be used for making phonograph records. Where the device is to be used as a telephone transmitter an ordi-

- nary microphone will be positioned so that its diaphragm occupies the same position as the diaphragm 1, and as the adaptation will be readily understood by those skilled in the art I have not shown a microphone in the drawing.
- The diaphragm 1 is shown as placed in a rabbet 2 of a member 3, and clamped between the washers 4 and 5 by means of a metal ring 6 which is secured to the member 3; as by means of the screws 7. In other words, the diaphragm is fastened around its edge, preferably by means commonly used in the art.
- The stylus lever or holder 8 may be of any approved form and the one shown herein has one end fastened at 9 to the center of the diaphragm. The lever is fulcrumed at 10 to a bearing plate 11 secured to the member 3; and a suitable recording stylus 12 is held in the socket 13 on one end of the lever. The vibrations of the stylus lever are traced on the record 14 revolving beneath it. It will be understood that the device is adapted for use with any form of stylus lever known in the art, the one herein being shown only by way of example.
- The diaphragm 1 is the recording or transmitting diaphragm on which the sound waves are to be impressed. It may correspond in size with the recording diaphragms now generally used but where my invention is used in its entirety the diaphragm 1 may be larger than those now used without encountering the disadvantages heretofore met with.
- The numeral 3 indicates the outer member of the concentrator, and while this may be varied in shape it is desirable that its interior be of decreasing area from its forward end 15 toward the end having the diaphragm 1. I find the most satisfactory results are attained when the bore 16 of the member 3 has a constant taper from its forward end 15 to the end having the diaphragm 1. It is preferable that the angle of taper be long as the length in proportion to the diameter of the larger end of the bore affects the sensitiveness of the instrument.
- In present practice the horn corresponding to the member 3 is usually hollow, so that it contains a large body of air which makes the horn act as a resonator, rather than as a concentrator of the sound waves.
- In the present case the body of air is reduced so that it has no appreciable resonance.
- In the preferred structure I provide an inner member which I shall here refer to as a core and which is designated as 17. This core is positioned within the member 3 and it is held in spaced relation to the latter to form an air space of the shape of a hollow cone. The sleeves 18 inserted between the core 17 and the inner surface of the member 3 hold the core separated from the latter, while screws 19 passing through the member 3, the sleeves 18 and into the core, secure the latter against displacement. I have shown four such sleeves and screws near each end of the core but the number and positions of the spacing and securing means are not important and any other device may be used for the purpose.
- The core 17 is preferably of the general shape of a frustum of a cone. In the form herein shown the core has a broad, flat forward surface 20, from which the core tapers gradually smaller to its rear end and the latter is shown as curved at 21 so that the space 22 between the core and diaphragm gradually decreases from the outer portion of the diaphragm toward the center thereof. In the preferred construction the outer surface of the core is parallel with the inner surface of the member 3 for the greater portion of the length so that there is formed between the core and member 3 an air space 23 in the form of a hollow cone and this space merges into the space 22 between the smaller end of the core and the diaphragm 1.
- Some part of the inclosing means is made of very resonant material and preferably this comprises a diaphragm or equivalent means disposed across the large end of the member 3. I have shown washers 24 at the large or forward end of the member 3 and between these there is clamped a diaphragm 25 the parts being secured in place by a ring 26 which is secured by screws 27 extending into the end of the member 3. The diaphragm 25 closes the larger end of the member 3 and it is separated from the forward end of the core to form an air space 28 which communicates, around the edge of the core 17 with the air space 23. Preferably, the diaphragm 25 is parallel with the front surface 20 of the core.
- In using the device to impress sound waves on the diaphragm 1, whether the latter be used for recording the waves on a phonograph record or for any other purpose, the larger end will be directed toward the source of the sound waves. The sound waves will strike the diaphragm 25 and this will be set into vibration thereby. The vibrations set up in the diaphragm 25 will cause the air in the spaces 28, 23, 22 to be vibrated and the air in turn will set up corresponding vibrations in the diaphragm 1. Each time the diaphragm 25 bends inwardly or toward the core it causes the diaphragm 1 to bend outwardly in the center and, vice, versa, when the diaphragm 25 bends away from the core it causes the diaphragm 1 to bend inwardly at the center.
- The sensitiveness of the device or the extent to which the diaphragm 1 is flexed in response to a given sound wave depends to a great extent upon the superficial area of

the large diaphragm 25. To some extent it depends upon the distance the diaphragm 25 is from the source of the sound, but in the present case sounds originating some distance from the instrument have a greater effect on the diaphragm 1 than in instruments heretofore used. This is due to the fact that the resonance of the device, *i. e.* the tendency to reflect or throw out, the sound waves is less by reason of the small air space within the concentrator. With a large diaphragm 25 and a space at 28 of large area the sensitiveness of the device is just as pronounced, and in fact, more so, than if the whole interior of the member 3 were merely filled with air. But while obtaining the effect of a large area, thus utilizing a large portion of the energy of the sound waves from the source of the sound, nevertheless, the present device eliminates the resonant effect of the large body of air. I believe that the less air there is in the member 3 the less the wall of this member tends to reflect the sound waves back toward their source or away from the diaphragm 1.

In the complete embodiment of my invention the entire air space in the member 3, *i. e.*, the spaces 28, 23 and 22 are all sealed or entirely closed, so that any bending of the large diaphragm 25 will more completely compress the air in the device and this will more perfectly transmit the energy to the diaphragm 1. To a certain extent, the smaller the body of air contained in the device the stronger it is compressed by the diaphragm 25 and therefore, the more completely the action is transmitted to the diaphragm 1.

It will be noted that the area of the air space 23 decreases from the position near the diaphragm 25 toward the diaphragm 1 and this causes the rather short vibrations of the diaphragm 25 to be translated into movements of great amplitude in the diaphragm 1.

In the preferred construction shown herein the air waves approach the diaphragm 1 around the outer portion or near the edge and they then converge toward the center. A compression forces the diaphragm 1 to bend outwardly at the center, the compression being absorbed or lost by this bending action. Conversely, a rarefaction causes the diaphragm 1 to bend inwardly at the center and it is lost or absorbed by this bending action. A given wave, once it has moved the diaphragm 1 ceases and it does not recross the diaphragm as might be the case if the waves were applied to the diaphragm as in former practice.

In the preferred construction the core 17 and member 3 are made of wood, preferably pine, spruce or some such wood which possesses the characteristic of bending to all tone waves. With a device made of such

material none of the quality of the sound waves is lost in the concentrator, so that not only the principal tones but all the overtones or harmonics are also impressed on the diaphragm 1. But, as distinguished from former devices, the recordings will be loud, notwithstanding that the device is made of wood, because the resonance or reflecting characteristic is reduced.

The characteristic "blasting" of former devices is eliminated, and I attribute this to a great extent to the comparatively low resonance of the device.

The best results are obtained if the core 17 is made solid, or, if partially hollow; then the wall should be thick in order that the core shall not be resonant to the sounds acting on the device. It is advantageous also, to have the wall of the member 3 thick, for the same reason.

The present device may be made as large as desired. The length may be extended and the diaphragm 25 increased so that it shall be several feet in diameter without having the counteracting disadvantages of previous devices. I have found that the thinner the diaphragm 25 in proportion to its area the more sensitive the device is to sound waves.

I have described my device above as a recorder or transmitter in which sound waves from a source of sound act on a larger diaphragm so that the waves are ultimately impressed on the smaller or recording diaphragm. I desire to be protected, however, in all uses to which the device is adapted, and the claims herein are intended to cover my invention even though it be used in other ways. For instance, the device may be used in the reverse way to that described above, in which case it may be employed as a telephone receiver or as a phonograph reproducer.

The stylus lever 8 may be vibrated by means of an ordinary phonograph record so that the sound waves previously recorded on a record are impressed on the diaphragm 1, the same as the waves are impressed or reproduced on the diaphragms of the ordinary reproducer, or, a telephone receiver may be positioned so that its diaphragm occupies the position occupied by the diaphragm 1. If the diaphragm 1, or, in the latter case, the receiver diaphragm be vibrated to reproduce sounds the waves created at the smaller end of the present device will traverse the spaces, 22, 23 and 28 in the reverse direction to their movement when the device is used as a recorder. The waves will act on the diaphragm 25 and the movement of the latter will cause pulsations of the air at its outer side and reproduce in the room the sounds represented by the groove of the phonograph record or the electrical impulses received over the electric circuit.

The diaphragm 25 will move in unison with the diaphragm 1 and even if the extent of its movement is not as great as the diaphragm 1 nevertheless, owing to its greater superficial area it will displace a comparatively large body of air and this will have the effect of amplifying the sound. The device will amplify the sound waves so that they are reproduced as loud as or louder than if the waves were created in the ordinary reproducer and sent through a tone arm and horn as is now done. But the reproduction will be free of that unnatural hollow effect always present in machines which use the hollow horn for amplifying. The device sounds as if the waves were actually reproduced in the first instance at the diaphragm 25, even if, as a matter of fact, they are not so reproduced. Owing to the small air space in the device as compared with amplifying horns now used the unnatural roundness or overfullness is eliminated. This also makes it possible to provide a very large amplifier for creating very intense sound waves and without the increasing hollowness which always results when increasing the size of the hollow horn amplifier.

In describing details of one embodiment of my invention and in referring to certain preferred proportions or materials I do not wish to be understood as limiting myself thereto except in such of the following claims as positively include such limitations.

Having described my invention, what I claim is:

1. A device of the class described comprising a smaller diaphragm, a larger diaphragm, and spaced members forming a tapering fluid space of annular cross section and with which members said diaphragms are so associated that the vibrations of one of said diaphragms are transmitted to the other of said diaphragms through the fluid in said space.

2. A device of the class described comprising a smaller diaphragm, a larger diaphragm, and spaced members forming a tapering fluid space of annular cross section and of gradually decreasing area and with which members said diaphragms are so associated that the vibrations of one of said diaphragms are transmitted to the other of said diaphragms through the fluid in said space.

3. A device of the class described comprising an outer member having a tapering bore, a core in said member and spaced therefrom to form a fluid space around the core and diaphragms arranged in spaced relation to said core and adapted to transmit sound vibrations from one to the other thereof through the fluid in said space around said core.

4. A device of the class described comprising

an outer member having a tapered bore, a tapered core in said outer member and spaced therefrom to form a fluid space of gradually decreasing area around the core, a larger and a smaller diaphragm arranged in spaced relation to said core and adapted to transmit sound vibrations from one to the other thereof through the fluid in said space and around said core.

5. A device of the class described comprising an outer member, a tapered core therein and spaced therefrom to form a fluid space of annular cross section, a smaller diaphragm, arranged in spaced relation to the smaller end of said core and a larger diaphragm arranged in spaced relation to the larger end of said core, said diaphragm being adapted to transmit sound vibrations from one to the other through the fluid in said spaces.

6. A device of the class described comprising an outer member, a tapered core therein and spaced therefrom to form a fluid space of annular cross section, a smaller diaphragm, arranged angularly to the axis of said core and spaced from the smaller end thereof and a larger diaphragm arranged at an angle to the axis of the core and in spaced relation to the larger end thereof, said diaphragms being adapted to transmit sound vibrations from one to the other through the fluid in said spaces.

7. A device of the class described comprising an outer member having a tapered bore, a tapered core therein and spaced therefrom to form a fluid space of annular cross section, a smaller diaphragm, arranged in spaced relation to the smaller end of said core and a larger diaphragm arranged substantially parallel and in spaced relation to the larger end of said core, said diaphragms being adapted to transmit sound vibrations from one to the other through the fluid in said spaces.

8. A device of the class described comprising an outer member made of wood, an inner core made of wood and spaced from said outer member to form a fluid space between them of annular cross section and of gradually decreasing area, a smaller diaphragm spaced from the smaller end of said core and a larger diaphragm spaced from the larger end of said core, said diaphragms being adapted to transmit sound vibrations from one to the other through the fluid in said spaces.

9. A device of the class described, comprising a smaller diaphragm on which the sound waves are to be impressed, means associated therewith for recording sound waves on a phonograph record, a larger diaphragm adapted to be acted upon by sound waves and means forming a fluid space and with which said diaphragms are so associated that the vibrations of said larger diaphragm will

be transmitted to said smaller diaphragm through the fluid in said space.

10. A device of the class described comprising an outer member made of wood and 10
15 having a tapered bore, a core made of wood and arranged in said first member to form a fluid space around the core and diaphragms

arranged in spaced relation to said core and adapted to transmit sound waves from one to the other through the fluid in said space around said core.

Signed at the city, county and State of New York this 23rd day of January, 1918.

CHARLES G. HENSLEY.
